UNITED STATES PATENT OFFICE.

FREDERICK WEHINGER, OF WATERBURY, CONNECTICUT, ASSIGNOR TO WATERBURY CLOCK CO., OF WATERBURY, CONNECTICUT, A CORPORATION.

SHIP'S-BELLS CLOCK.

1,390,848.

Specification of Letters Patent. Patented Sept. 13, 1921.

Application filed June 24, 1920. Serial No. 391,448.

To all whom it may concern:

Be it known that I, FREDERICK WEHINGER, a citizen of the United States, residing at Waterbury, in the county of New Haven and State of Connecticut, have invented a new and useful Improvement in Ships' Bells Clocks; and I do hereby declare the following, when taken in connection with the accompanying drawings and the characters of reference marked thereon, to be a full, clear, and exact description of the same, and which said drawings constitute part of this application, and represent, in—

Figure 1, a view in front elevation of a ship's bells clock constructed in accordance with my invention, the time-train of the clock being omitted.

Fig. 2, a view of the clock in left-hand side elevation, showing the pin-wheel.

Fig. 3, a detached perspective view of the pin-wheel.

Heretofore ships' bells clocks have generally been furnished with a rack-and-snail striking mechanism modified as required for sounding ship's bells and open to the objections of being complicated and therefore expensive to construct, and difficult to adjust. The object of my invention is to produce a ship's bells clock in which the sounding of ship's bells is effected by extremely simple, inexpensive, and reliable means. With these ends in view, my invention consists in a pin-wheel carrying pins arranged singly and in pairs, in combination with a count-wheel having its deep notches arranged to complement the arrangement of said pins.

My invention further consists in certain details of construction as will be herein after described and pointed out in the claims.

In carrying out my invention, as herein shown, I employ a pin-wheel 2 (Fig. 3) having a series of pins set into its outer face in accordance with the plan of ship's bells, under which plan the twenty-four hours of a day are divided into six "watches" of four hours each, the division of the watches being marked by bells running from one to eight. Thus, the wheel 2 is provided with a single pin 3 which stands for "one bell", denoting the expiration of the first half-hour of a watch. The pair of pins 4, 4 succeeding to the pin 3 stand for "two bells", indicating the expiration of the first hour

of the watch. The next succeeding group of pins consists of a pair of pins 5, 5 followed by a single pin 5, and stand for "three bells", denoting the expiration of the first hour and a half of the watch. The 60 pins 5, 5, and 5 are succeeded by a group consisting of two pairs of pins 6, 6 and 6, 6 sounding "four bells", denoting the expiration of the second hour of the watch. The two pairs of pins, 7, 7, 7, 7 and the 65 single pin 7 stand for "five bells"; the three pairs of pins 8, 8, 8, 8, 8, 8 stand for "six bells"; the three pairs of pins 9, 9, 9, 9, 9, 9 and the single pin 9 stand for "seven bells"; while the four pairs of pins 10, 10, 10, 10, 70 10, 10, 10, 10 stand for "eight bells" and complete the watch.

In conjunction with a pin-wheel having such a grouping of single pins and pairs of pins, I employ a count-wheel 11 having its 75 teeth 12 and deep notches 13 arranged on the same principle as the pins in the pin-wheel, except that the teeth 12 are not arranged in pairs, though the deep notches 13 correspond in arrangement to the single pin 80 3 and to the terminations of the several groups of pins upon the pin-wheel 2. As shown, the count-wheel has three complete groups of notches corresponding to the single group of pins upon the pin-wheel, but 85 this is not imperative, as the number of groups of notches in the count-wheel may be varied as desired so long as the pin-wheel and count-wheel are geared in the proper ratio. I prefer, however, to provide the 90 count-wheel with a plurality of groups of notches, since such a construction permits the count-wheel to be geared so as to revolve very slowly, which is highly important in eight-day clocks, where a rapid rotation of the count-wheel would be undesirable. Furthermore, the employment of a relatively large count-wheel facilitates the arrangement of the count-hook so as to avoid interference with other parts of the 100 movement.

As shown, the pin-wheel 2 and count-wheel 11 are co-axially mounted upon the winding-arbor 14, the pin-wheel 2 having a hub 15 carrying a gear 16 meshed into by 105 a gear 17 on the main pinion-staff 18 of the strike-train, which is not fully shown. The count-wheel 11 is driven by a pinion 19 upon the staff 18, these wheels and pinions being proportioned so that the pin-wheel is 110

geared to travel three times as fast as the count-wheel.

The pins of the pin-wheel co-act with a hammer-operating finger 20 in a rock-shaft 5 21 mounting the hammer-wire 22 of the hammer 23 which strikes the bell 24. On the other hand, the teeth 12 and deep notches 13 of the count-wheel co-act with a count-hook 25 hung upon a rock-shaft 26 10 operated by a two-notched cam 27 on the third wheel-staff 28 of the strike-train.

The particular mounting and operation of the pin- and count-wheels will be varied in accordance with the size and character of 15 the clocks in which my invention may be embodied, my invention being characterized by a pin-wheel provided with pins arranged singly and in groups in accordance with the characteristic sounding of ship's bells. 20 By arranging the pins singly and in groups in the pin-wheel, I am enabled to effect, with a single hammer, a snappy striking of ship's bells with those sensible intervals between the pairs of bells and the single 25 bells necessary to enable the time to be accurately told, while by driving the pin-wheel at a higher speed than the count-wheel, I am enabled to revolve the count-wheel with sufficient slowness to permit the free 30 action of the count-hook in its deep notches, which can, of course, be no wider than the spaces separating its teeth, from which it follows that if the count-wheel is revolved too rapidly, the count-hook is liable to foul 35 in its deep notches.

I claim:

1. A ship's bells clock having a strike-train including a pin-wheel, pins mounted therein singly and in pairs, in accordance 40 with the divisions of ship's bells, and a hammer-operating member acted upon in sequence by all of the said pins, whereby, by arranging the bells singly and in pairs, com-

pensatory spaces are provided between them for the reception of the hammer-operating 45 member and mis-striking avoided.

2. In a ship's bells clock, the combination with a pin-wheel, of pins mounted therein singly and in pairs in accordance with the divisions of ship's bells, a count-wheel having its notches arranged on the principle of ship's bells, a single hammer acted upon in sequence by all of the said pins, a count-hook coacting with the count-wheel, and means for driving the pin-wheel at a relatively 55 greater speed than the count-wheel.

3. In a ship's bells clock, the combination with a pin-wheel, of pins mounted therein singly and in pairs in accordance with the divisions of ship's bells, a count-wheel having a plurality of groups of notches arranged on the principle of ship's bells, a single hammer acted upon in sequence by all of the said pins, a count-hook coacting 60 with the count-wheel, and means for driving the said wheels at speeds determined in relativity by the number of groups of notches in the count-wheel.

4. In a ship's bells clock, the combination with a pin-wheel, of pins mounted therein 70 singly and in pairs in accordance with the divisions of ship's bells, a coaxially-mounted count-wheel having a plurality of groups of notches, of which the notches of each group cover the entire cycle of pins in the pin-wheel, a count-hook coacting with the count-wheel, and means for driving the pin-wheel 75 as many times faster than the count-wheel as the count-wheel has groups of notches.

In testimony whereof, I have signed this 80 specification in the presence of two subscribing witnesses.

FREDERICK WEHINGER.
